(57) **CLAIM**

The ornamental design for a lid dispenser, as shown and described.

DESCRIPTION

FIG. 1 is an elevational front view of a lid dispenser according to a first embodiment, showing our new design; FIG. 2 is an elevational back view of the lid dispenser; FIG. 3 is a top plan view of the lid dispenser;

FIG. 4 is a bottom plan view of the lid dispenser; FIG. 5 is an elevational left side view of the lid dispenser; the elevational right side view is a mirror image of the left side;

FIG. 6 is a perspective front view of a lid dispenser; FIG. 7 is a perspective back view of the lid dispenser; FIG. 8 is a perspective front view of a lid dispenser according to a second embodiment, showing a minimally modified form of a lid dispenser, wherein a front cover is placed over the dispenser opening; FIG. 9. is an elevational front view thereof; and,

FIG. 10 is a perspective front view thereof, with a lid positioned in the dispenser and ready to be dispensed. The broken lines in the drawings are for the purposes of depicting parts of the lid dispenser that form no part of the claimed design.
